UNITED STATES PATENT OFFICE

159,112

CIRCUIT BREAKER

Anthony Van Ryan, South Milwaukee, Wis., assignor to McGraw Electric Company, Milwaukee, Wis., a corporation of Delaware

Application March 23, 1948, Serial No. 145,285

Term of patent 14 years

(Cl. D26—5)

To all whom it may concern:

Be it known that I, Anthony Van Ryan, a citizen of the United States, residing at South Milwaukee, in the county of Milwaukee and State of Wisconsin, have invented a new, original, and ornamental Design for Circuit Breakers, of which the following is a specification, reference being had to the accompanying drawings, forming part thereof.

Fig. 1 is a perspective view of the circuit breaker showing my new design.

Fig. 2 is a top plan view of the circuit breaker.

Fig. 3 is a front elevational view thereof.

The dominant features of my design reside in that portion shown in full lines in the drawing.

I claim:

The ornamental design for a circuit breaker, substantially as shown and described.

ANTHONY VAN RYAN.
